LIP STICK HOLDER

Filed April 2, 1934

UNITED STATES PATENT OFFICE

2,000,487

LIP STICK HOLDER

Arthur A. Koch, Beardsley, Minn.

Application April 2, 1934, Serial No. 718,699

7 Claims. (Cl. 206—56)

The invention relates to holders for lipsticks, and the like, and has for its principal object the provision of means whereby the lipstick will always be held in position for immediate use including means for yieldingly moving the lipstick out of its container and to automatically hold the lipstick for use.

A further object of the invention is the provision of a lipstick holder including a casing to contain the lipstick and provided with a spring actuated follower normally tending to project the lipstick outwardly of the casing, and including clamping devices pivotally mounted in the casing to engage the lipstick and hold it from movement by the spring actuated follower, and a cover slidably engaging the casing and provided with means to release the clamping devices when the cover is engaging the casing and thereby permit reaction of the spring actuated follower to automatically adjust the lipstick for reuse on removal of the cover.

The construction and operation of the invention will be described in detail hereinafter and the construction will be found illustrated in the accompanying drawing, in which

Figure 1 is a view in elevation of the lipstick holder,

Figure 2 is a longitudinal sectional view,

Figure 3 is a similar view with the cover removed,

Figure 4 is a fragmentary longitudinal sectional view on a plane indicated by the line 4—4 of Figure 1, and

Figures 5, 6, and 7 are transverse sectional views on planes indicated by the lines 5—5, 6—6, and 7—7, respectively of Figure 3.

In the drawing similar reference characters are used to designate corresponding parts in all of the views.

The improved lipstick holder includes a cylindrical casing 10 made preferably of sheet metal and having a bottom section 11 secured thereto by means of a seam 12 and provided with a reduced extension 13 to receive the thrust of a spring 14 mounted in the casing and having the other end of the spring secured to a cup-shaped follower 15 in which is seated the lower end of a lipstick 16, said spring and follower tending to normally project the lipstick outwardly of the open end 17 of the casing.

18 designates inwardly offset ears on the tubular member 10 on which are pivotally mounted arcuate clamping members 19 as shown at 20, said clamping members being held normally in clamping engagement with the lipstick 16 by means of

an open spring ring 21 having one of its ends bent inwardly as shown at 22 through an opening 23 in one of the clamping members 20. The outer free ends of the arcuate clamping members 19 are provided with flanges 24 that extend rearwardly of said clamping members and are inclined outwardly of the casing as shown.

The container also includes a cover having a tubular portion 25 and a closed end 26 that is secured by means of a seam 27 to said tubular portion 25 and having a reduced extension 28 providing a shoulder 29, that when the cover is placed in position by sliding it on the tubular member 10, said shoulder 29 engages the flanges 24 to open the arcuate clamping members 19 so that the spring actuated follower 15 may project the free end of the lipstick 16 into the reduced portion 28 until stopped by the closed end thereof.

The operation of the device is as follows:

When the cover is removed as shown in Figure 3, the lipstick will be held in the position shown therein. When the cover is returned to position on the open end of the tubular member 10, the shoulder 29 will engage the flanges 24, as hereinbefore stated, and moves the clamping members 19 into the position shown in Figure 2, and the lipstick 16 will be moved forward by the spring 14 and the follower 15 into position for use thereof when the cover is again removed.

I have described the article for use in holding a lipstick, but it will be apparent that any other material in stick form may be substituted therefor, such for instance as chalk, crayon, marking pencils, etc.

What I claim is:—

1. In a lipstick holder, a casing adapted to contain a lipstick, yielding means engaging the lipstick to normally project it from the casing, clamping jaws pivotally mounted in said casing and adapted to yieldingly engage the lipstick, 40 spring means jointly engaging said jaws and unitarily moving them into clamping positions, and a cover for the casing provided with means to move said clamping jaws from engaging position.

2. In a lipstick holder, a casing adapted to contain a lipstick, a spring actuated follower in said casing to normally move the lipstick outwardly of the casing, clamping jaws pivotally mounted in said casing to engage the lipstick and hold it against the action of said follower, spring means jointly engaging said jaws and unitarily moving them into clamping positions, a cover for the casing and provided with means to release the clamping jaws from engaging position.

3. In a holder for lipsticks, an elongated casing, a resiliently actuated follower mounted in said casing and adapted to engage a lipstick, clamping jaws pivotally mounted in said casing, a spring ring, jointly engaging said jaws to yieldingly hold them in engagement with the lipstick, a cover for said casing, and means actuated by the cover to release said clamping jaws from engaging position.
- 10 4. In a holder for lipsticks, an elongated casing, a spring actuated follower mounted in the casing and adapted to engage a lipstick, clamping jaws pivotally secured in the casing, a spring ring jointly engaging said jaws to yieldingly hold said clamping jaws in engagement with the lipstick, said clamping members having flanges inclined outwardly of the casing, a cover for said casing, and a shoulder on said cover engaging said flanges to release said clamping members from engaging positions.
- 15 5. A lipstick holder, comprising a casing, means in the casing mounting a lipstick and normally tending to project it from the casing, arcuate clamping jaws pivotally mounted in the casing, a spring ring jointly engaging said jaws to yieldingly hold them in engagement with the lipstick, a cover slidably engaging the casing, and a shoul-
- der on said cover to engage said jaws and move them from engaging positions.
6. A lipstick holder, comprising a casing, a spring actuated follower in the casing to mount a lipstick, arcuate clamping jaws pivotally secured in the casing, a spring actuated ring engaging said jaws to unitarily hold them in engagement with the lipstick, flanges on the free ends of said jaws inclined rearwardly thereof and outwardly of the casing, a cover for the casing provided with a reduced extension providing a shoulder, said shoulder being adapted to engage said flanges to move said jaws from engaging positions.
- 10 7. A lipstick holder, comprising a casing, a spring actuated follower in the casing to mount a lipstick, arcuate jaws pivotally secured in the casing, an annular spring member secured at one of its ends to one of the jaws and enclosing said jaws, said spring member unitarily holding the jaws in clamping positions with the lipstick engaged therebetween, outwardly and rearwardly directed flanges on the free ends of said jaws, a cover for the casing, and a circumferential shoulder on said cover to engage said flanges and move the jaws from engaging positions.
